UNITED STATES PATENT OFFICE.

WILLIAM M. SANFORD, OF HARTFORD, CONNECTICUT.

RENEWABLE RUBBER-HEEL DEVICE.

1,113,695.

Specification of Letters Patent.

Patented Oct. 13, 1914.

Application filed March 25, 1914. Serial No. 827,084.

To all whom it may concern:

Be it known that I, WILLIAM M. SANFORD, a citizen of the United States, residing at Hartford, in the county of Hartford and 5 State of Connecticut, have invented certain new and useful Improvements in Renewable Rubber-Heel Devices, of which the following is a specification.

My invention relates to renewable rubber heel devices, and the object of my improvement is to produce a device that can be applied to the heels of shoes of different sizes and in a manner permitting of readily removing the same and which device is provided with tread devices of suitable material, such as rubber in some cases and metal in other cases, or other material as desired, and which tread devices may be replaced when worn or may be changed for 20 other reasons if desired.

Primarily my device is intended to serve as a rubber heel, but in some cases the rubber tread devices may be removed as a whole or in part and metal elements substituted 25 therefor so that the device may be used as a creeper to prevent slipping on ice.

In the accompanying drawing:—Figure 1 is a plan view of my improved rubber heel device. Fig. 2 is a reverse view of the same. 30 Fig. 3 is plan view of the same in open position. Fig. 4 is a side elevation of the same, the flange being in part broken out. Fig. 5 is a plan view of the left member. Fig. 6 is a similar view of the right member. Fig. 7 35 is a rear elevation of the complete device in which some of the rubber tread devices shown in the other figures are replaced with others of metal. Fig. 8 is a side elevation of one of the metal tread devices shown in 40 Fig. 7.

My improved heel device comprises a pair of members, respectively a left member 10 and a right member 11 pivotally connected adjacent the rear end by means of overlapping ears 12 and a pivotal pin 13 and which combined are of suitable size and shape to fit over a heel generally and which may be closed in or opened out more or less to accommodate heels of different sizes, and 45 which furthermore, are provided with locking means, to be described, to lock the same in the adjusted position. Lugs 14 are provided that engage with the material of the heel to hold the device in position on the heel. Holes 15 are provided in the members 50 10 and 11 in which are housed tread devices

16 of rubber or 17 of metal as the case may be. The members 10 and 11 are made of sheet metal and comprise each a central body portion, a flange 18 along the outer lateral and rear edges, and the lugs 14 integral with the free edges of the said flange 18. 60

The tread devices 16 and 17 comprise each a cylindrical body portion 19 that is a fit for the holes 15 and a relatively enlarged head 20 at the upper end of the same. The body portion 19 is of appreciable length, suitable to extend below the lower surfaces of the body portions of the members 10 and 11 and so that the extreme lower end may 65 serve as the tread proper when in use. The said tread proper 21 of the rubber devices 16 is flat or plane, and will be worn away in use.

The tread proper 21^a of the metal tread 70 devices 17 is roughened suitably to engage with ice or other surface with which it is desired to make a positive and firm hold, and the same may be hardened.

The flanges 18 are made of proper depth 75 to permit of housing the heads 20 between the body portion of the members 10 and 11 and the under surface of the heel on which the device is mounted. The lugs 14 comprise a pair at the rear as shown and a pair 80 near the forward end of the device, it being understood that a greater number of lugs 85 may be provided if desired.

The locking means comprise a swinging member 22, pivotally connected by one end 90 to the body portion of the left member 10 by means of a pivotal pin 23 and the other end overlying the body portion of the right member 11, and which other end is provided on the rear edge with a rack 24; a lug or stop 25 on the right member 11 suitable for engaging with the said rack 24; and spring means for normally holding the said rack 24 engaged with the stop 25. As shown, I utilize for the said spring means one or 95 more of the rubber tread members 16 and I do this by positioning one of the holes 15 so that the head 20 of the tread member that is housed therein and which overhangs the said hole 15, will be in bearing engagement with the front edge 26 of the slide member 22. The said front edge 26 and the rack 24 are both curved suitably to hold one of the teeth of the rack 24 engaged with the stop 25 for the different positions of 100 adjustment of the members 10 and 11 throughout the range desired, with the head 105

20 engaged with the said front edge 26 as shown in Fig. 1.

The head 20 being made of rubber the same serves as a spring member and therefore, while normally holding the locking member in the locked position as described, because of the resiliency of the rubber, the same will yield to an excessive pressure, such as is applied in placing the device in 10 position on the heel of a shoe.

In applying the device to a heel the members 10 and 11 are opened out; the device is placed on the heel with the heads 20 in abutment with the lower surface thereof; 15 the rear lugs 14 are embedded in the material of the heel; the outer portion of the rack 24 being engaged with the stop 25; and finally the device is closed against the heel, with the flanges 18 bearing against the 20 lateral wall thereof, and the front lugs 14 being embedded in the material of the heel.

When in position on the heel there is a slit-like space 27 between the opposed edges of the members 10 and 11 and which permits 25 of access to the slide member 22 with a sharp or flat and thin implement and whereby the slide member 22 may be pushed back to free the rack 24 from the stop 25, when the device may be readily removed from the 30 heel. The stop 25 as shown is formed by turning up an integral flange on the inner edge of the body portion of the right member 11.

It will be noted that the teeth of the rack 35 24 are so formed as to permit of forcibly closing the device against the heel when being placed in position and to resist opening the same without directly manipulating the member 22. That is to say in

applying the device to a heel pressing the 40 mating left and right members 10 and 11 together to close them against the heel operates automatically to move the swinging member 22 back and forth so as to slide the rack 24 along the stop 25 until the 45 amount of closing has been effected, and the device is finally locked when such amount of closing has been effected.

What I claim as my invention is:—

1. A heel device comprising a pair of 50 members pivotally connected together and having tread devices, flanges on the said members having lugs suitable to be embedded in the material of a heel, and a locking device comprising a swinging arm pivotally mounted by one end on one of the said members and having a rack, a stop on the other of the said members, and resilient means for holding the said rack engaged with the said stop and the said locking device being housed in the space between the 60 said flanges.

2. A heel device comprising a pair of members pivotally connected together and having tread members and having means 65 for being secured to a heel comprising lugs for engaging with the side of the heel and a locking device comprising a swinging member on one of the said pair of members having a rack and a stop on the other of the 70 said pair of members and one of the said tread members being arranged to serve as a spring member to hold the said rack engaged with the said stop.

WILLIAM M. SANFORD.
